Patented Oct. 7, 1975

237,108

EYEGLASS HOLDER

Jerome Mende, 109 Roman Ave.,
Staten Island, N.Y. 10314

Filed Sept. 17, 1973, Ser. No. 398,204

Term of patent 14 years

Int. Cl. D3—02

U.S. Cl. D57—1 C

FIG. 1

FIG. 2

FIG. 4

FIG. 3

FIG. 1 is a perspective view of an eyeglass holder showing my new design;

FIG. 2 is a reduced scale top plan view;

FIG. 3 is a front elevational view thereof; and

FIG. 4 is a left side elevational view thereof.

I claim:

The ornamental design for an eyeglass holder, as shown and described.
